UNITED STATES PATENT OFFICE.

PAUL OSCAR WELS, OF LOS ANGELES, CALIFORNIA.

CENTRIFUGAL CONCENTRATOR.

1,064,184.

Specification of Letters Patent. Patented June 10, 1913.

Application filed September 16, 1911. Serial No. 649,747.

To all whom it may concern.

Be it known that I, PAUL O. WELS, a citizen of the United States, residing at Los Angeles, in the county of Los Angeles and State of California, have invented new and useful Improvements in Centrifugal Concentrators, of which the following is a specification.

This invention relates to centrifugal concentrators, and the object of the invention is to concentrate finely crushed ores or slimes; to provide means in centrifugal concentrating machines for separating an enriched and an impoverished product from the ore, and for imparting definite motion of the concentrates toward one end of the machine while the tailings are carried to the other, so that they can be separately discharged; to provide means for washing the concentrates with clear water before they are discharged; and to provide a concentrating machine which will carry on the process of concentration continuously.

Other objects and advantages will be brought out in the following description of the machine.

In these specifications, the machine is presented in two embodiments which are associated and identified in objects and principles.

Referring to the drawings: Figure 1 is a sectional vertical view through one form of the machine, a part of the drum being in elevation. Fig. 2 is a plan view of Fig. 1. Fig. 3 is a section on line x^3-x^3 Fig. 1. Fig. 4 is a vertical section through another form of the machine. Fig. 5 is a vertical section through a portion of the outer casing and inner drum, showing one form of combination of the riffles and ribs. Fig. 6 is a view similar to Fig. 5, showing another form of combination of riffles and ribs. Fig. 7 is a view similar to Fig. 5, showing another form of combination of riffles and ribs. Fig. 8 is a vertical sectional view through a portion of the outer shell, showing the inner drum in elevation, and illustrating parallel riffles and parallel ribs. Fig. 9 is an elevation of a portion of the inner drum detached. Fig. 10 is a vertical sectional view through a portion of the outer casing and the inner drum, showing the absence of

riffles on the casing in combination with the conveyer on the drum. Fig. 11 is a plan view of a portion of the inner drum, 55 showing a plan view of interrupted blades or rakes set at an angle. Fig. 12 is a plan view of a portion of the inner drum with the form of rib shown in Fig. 7. Fig. 13 is a plan view of a part of the conveyer 60 blades of Fig. 10, showing one form of perforations. Fig. 14 is a similar view to Fig. 13, showing perforations around the edges of the ribs in conjunction with other perforations. 65

1 designates a casing, provided with a hub 2 which is rigidly secured to a shaft 3. The upper end of the casing 1 has a rim 4 which extends over an annular launder 5, the bottom of which is constructed with a slight 70 pitch, to cause the discharge of the contents from the lowest point thereof.

6 designates a frame which is fastened at its lower end to a bed plate 7 having a bearing 8 in which the lower end of the 75 shaft 3 is mounted to rotate, while the upper portion of the frame 6 is provided with a bearing 9 in which the upper end of the shaft 3 is mounted.

The casing 1 is provided on its inner surface with a spiral riffle or riffles 10, which co-act with other parts of the apparatus to be described, to effect the separation of the concentrates and the tailings and to effect the definite movements of the concentrates 80 between the riffles to their points of discharge. By the word riffle, I not only mean a rectangular projection as shown in the drawings, but any corrugations that produce spiral offsets, the intent being to produce a spirally grooved surface. Various modifications of the rifled surface of the casing 1 are shown in Figs. 1 and 5 to 8, and they will be more fully described later. The casing 1 has an annular crowned portion 12, over which a belt may be run to impart rotation to the casing. 85 90 95

Within the casing 1 is a rotatable drum 13 on the outer wall of which are ribs 11 which, by their joint action with the riffles 10 on the casing produce the effects described above. The relations of the ribs 11 are further illustrated in Figs. 5 to 9, 11 and 12. They may be continuous spiral, or

vertical blades, or they may be interrupted blades, and will be further described later, the intent being to provide means on the inner drum to co-act with the riffles on the casing in effecting the separation of the concentrates and the tailings, and the moving of the concentrates.

The drum 13 has a partition 14 with an elongated hub 15 which is rotatable on the shaft 3. The upper portion of the drum 13 extends above the casing 1 and has a peripheral crowned portion 17 over which a belt may be run to rotate the drum 13. At its upper end, the drum has an annular opening 18 through which a pipe 19 projects for delivering the feed to the machine. Above the partition 14 the drum 13 has a series of openings 16 through which the feed of ore with water flows out, assisted by centrifugal force, into the channels 20 surrounding the drum. The flow of the current of the feed and the tailings is upward through the vertical and the spiral channels, both numbered 20 in the upper section of the machine, until it overflows at the tailings discharge 4. The lower section of the drum 13 commencing at the partition 14, is of larger diameter than the upper section, making the depth of the riffles 10 and the ribs 11, shallower in the lower portion than in the upper, and making the area of the channels 28 smaller than that of the channels 20. This is done in order to maintain the necessary velocity of current in the channels 28 for washing the concentrates, while using a suitable quantity of wash water.

The lower portion of the shaft 3 has a passage 21 which at the lower end communicates with a pipe 22 through which wash water is introduced, and the shaft is provided with a plurality of transverse passages 23 near the upper end of the passage 21, which communicates with passages 24 formed in a ring 25 which rotates with the shaft 3. Other passages 26 in the shaft 3 also communicate between the pipe 22 and the lower space of the drum 13. The wash water is thus supplied to the lower part of the machine and passes into the channels 28 between the drum and the casing. The lower part of the casing 1 is provided with several outlets 27 for the discharge of the concentrates which discharge into a variable depth launder 29 that surrounds the bottom 55 of the casing 1.

Referring to the details of the riffles 10, they may consist of one continuous riffle passing spirally over the inner surface of the casing 1, or they may be a series of parallel riffles. One modification of the riffle form is illustrated in Fig. 1 and a two riffle form of the parallel series is shown in Fig. 8. They may be inclined at any desired pitch to the horizontal, different pitches being illustrated

in the detail figures. These riffles 10 may be formed either directly on the casing 1, as shown in the detail Figs. 5 to 8, or on a lining 30, as shown in Fig. 1. The lining 30 may be of cast iron, sheet metal, etc. The ribs 11 on the inner drum may be inclined 70 at any desired angle with the riffles 10 on the casing, the ribs pitching either in the same direction as the riffles on the casing, as illustrated in Figs. 1 and 6, or pitching in the contrary direction as illustrated in Fig. 5, or they may be vertical blades as illustrated in Figs. 7 and 12, or interrupted circumferential blades or rakes set at any angle, one instance of which is shown in plan view in Fig. 11. The object of these detailed illustrations is to show some of the numerous modifications of projections 11 on the drum, which may be used to co-act with the riffles 10.

Referring to Fig. 4, the distinguishing 85 feature of this form of the invention is that the principal functions of both the riffles 10 on the casing as described for Fig. 1, and of the ribs or blades 11, Fig. 1, are in the form shown in Fig. 4, performed by the screw 90 conveyer 11' which is provided on the outer surface of the drum 13', and which will be described in detail later. The machine is shown with its shaft 3' mounted at its upper end in a bearing 9' and at its lower end in 95 a bearing 8'. An elongated rotatable hub 15' is provided for the drum 13', and is mounted on the shaft 3' as in the previous form, and the casing 1' is likewise keyed onto the shaft. Wash water is similarly 100 introduced through the pipe 22' and its communicating channels 21', 23', 24', and 26', into the interior of the machine, and into its washing channels 28'. The drum 13' has, as before, two sections of different diameters 105 above and below the partition 14'. There is a sprocket wheel 17' near the upper end of the hub 15', over which a chain may be run to impart rotation to the drum, and there is a crowned portion 12' for a belt to impart 110 rotation to the casing. Over the upper end of the drum 13' is a stationary headpiece 40 with which the upper end of the drum 13' has a watertight fit, and within which it revolves. The headpiece 40 is fastened to the 115 frame 6'. The feedpipe 19' having a watertight fit within the headpiece 40 enables the feed to be introduced under greater pressure than is illustrated in Fig. 1. From the interior of the drum 13', the feed enters the 120 concentrating channels 20' between the drum 13' and the casing 1', through the slotted opening 16'. The bottom of the casing 1' is provided with an enlarged space 41 in which several blades 42 revolve to stir 125 up and assist the concentrates to the discharge openings 27' which are here shown to be provided with spigots 43. The blades 42

are fixed to the hub 2', with which they revolve. There is an opening 44 in the bottom of the casing 1' for use as a handhole, which is closed with a cover 45 during the operation of the machine. On the upper rim 4' of the casing there is a removable plate or ring 46 which projects over the inner surface of the casing 1', overlapping the edges of the ribs of the conveyer 11'. The object of the ring 46 is to form a retaining means for the bed of ore that is held on the casing by centrifugal force. A flange 47 is attached to the upper portion of the drum 13', and overlaps the plate 46. A screw thread 48 is formed on the drum 13' and flange 47 is threaded to turn on the threads 48. Four blocks or keys 49 are set at 90° from one another, in key seats provided in the flange, and are tightened to the drum with the set screws 50. It is adjustable vertically and by means of it the distance between the plate 46 and the flange 47 may be regulated. Launders 5' and 29' are provided as in the previous instance. The ribs of the screw conveyer 11' have openings or perforations through the plates in order to permit the current of water and tailings to flow directly upward as well as around the spiral channels between the casing and the drum. The perforations may be of any form. Fig. 13 shows one form of perforations through the plates 11', and Fig. 14 the same with notches around the edges thereof. The conveyer ribs 11' make numerous turns around the drum 13' and are narrower in the lower or washing section of the machine than in the upper section.

Both forms of the machine operate substantially the same. In the embodiment shown in Fig. 1, a rapid rotation is imparted to the casing 1 and to the drum 13, with a differential speed, both rotating in the same direction. The drum may rotate slower or faster than the casing, and the direction of rotation depends upon whether a right or left handed thread is used for the riffles on the casing. The wash water is turned on, proceeding through the pipe 22 and its communicating passages into the interior of the machine, and the feed of finely crushed ore with water, is introduced through the pipe 19 into the drum 13, thence passing, assisted by centrifugal force, through openings 16 into the upper concentrating portion of the machine between the drum 13 and the casing 1. The feed progresses through the spaces or channels that exist between the casing and the drum and their projections, until the tailings overflow and escape at the upper end of the casing.

The machine is made to rotate at such speed that the heavier mineral seeks to adhere to the casing, but the speed is such that the tendency to adhere can be overcome by

the means described. The lighter minerals and gangue are held more lightly against the casing or remain in suspension in the water. The co-action of the riffles on the surface of the casing with the ribs on the surface of the drum, cause an agitating and scouring action which separates the tailings from the concentrates, permitting the currents of water to carry the tailings to their discharge and causing the concentrates to move down the casing between the riffles thereon, to the concentrates discharges. The water acquires rotation with the machine and due to the centrifugal force also an additional tendency to escape or overflow from the machine. The riffles on the casing and the ribs on the drum co-act to alter the speed of rotation of the water, and to cause the agitating and scouring action on the materials that are held in the depressions between the riffles on the casing, that effects the separation of the concentrates and the tailings and pushes the concentrates downward along the grooves between the riffles of the casing toward the concentrate outlets. When the drum rotates slower than the casing, the ribs or blades on its outer surface cause a lag of the water at the casing which effects the above separation and movement, and a similar effect may be produced by revolving the drum faster than the casing in which case there is an acceleration of the water at the casing instead of the lag. As the concentrates descend, they come to the narrower channels surrounding the greater diameter of the drum in which the washing or further cleansing of the concentrates is effected with clear water. The co-action of the riffles and the blades, is similar here to that in the upper section, to separate the lighter material and to move the concentrates downward. The concentrates pass out through several discharges and the tailings overflow into their respective launders.

In the second form shown in Fig. 4, the casing and the inner drum also revolve differentially in the same direction but the drum is the shaft of the conveyer. In the previous form, the spiral means for carrying the concentrates were on the casing, where as in the second form the casing is a retaining surface for the screw on the drum. In this form having a left hand screw on the conveyer or drum, the conveyer revolves slightly faster than the casing and both revolve clockwise looking down the machine Fig. 4. Essentially, the operation and the effects produced by the second form of the centrifugal concentrator are the same as those for the form previously described. The wash water is introduced as already described. The feed passes through the pipe into the stationary head of the drum thence

out through the openings into the concentrating space. A slightly stronger centrifugal force is employed than in the previous form. As in the first case the flow of the feed is upward through the vertical openings and around the spiral channels. The conveyer blades agitate the layer of mineral that forms on the casing, by actual contact, loosening the lighter tailings so that the currents may carry them to the tailings discharge, while the conveyer carries the concentrates to their respective discharge. The wash water channel is constricted for the same reasons as given for the first form and the method of using the wash water is the same. The ring over the casing assists in maintaining the aforesaid layer of ore on the casing and the overflow can be regulated by raising or lowering the flange on the drum. The stirrers agitate the concentrates in the enlarged part of the bottom of the casing, assisting them to the discharge spigots. The ultimate effects of the introduction of the feed intermediately between the ends of the machine into the concentrating channels, the agitation of the ore and its separation, the carrying off of the tailings, the conveying of the concentrates, and the washing of the concentrates in the specially provided channels, are the same in both forms of the machine.

What I claim is—

1. In a centrifugal concentrator, a revoluble casing, a revoluble drum within the casing, means for introducing feed into the space between the drum and casing, means for introducing wash water into the space between the drum and casing, and means between the drum and casing for causing movement of the concentrates in a direction opposite to that of the tailings.

2. In a concentrator, an outer revoluble casing, means for introducing feed into said casing at the inner wall thereof, spiral means within the casing for causing a progression of the concentrates away from the tailings by the relative movement between the spiral means and concentrates said spiral means having perforations and recesses on the edges thereof.

3. In a concentrator, a revoluble casing, spiral ruffles on the inner wall of the casing, a revoluble drum within the casing, projections on said drum, means for introducing feed into the space between the drum and casing, and means for introducing wash water into the space between the drum and casing.

4. In a concentrator, a revoluble casing, spiral ruffles on the inner wall of the casing, a revoluble drum within the casing, spiral ribs on said drum, and means for introducing feed into the space between the drum and casing.

5. In a concentrator, a revoluble casing, 65 spiral ruffles on the inner wall of the casing, a revoluble drum within the casing, spiral ribs on said drum, said spiral ribs having perforations, and means for introducing feed into the space between the drum and casing. 70

6. In a concentrator, an outer revoluble casing, a revoluble drum within the casing, the outer wall of said drum having two diameters, thereby forming a feed concentrating channel and a concentrate cleansing 75 channel of less width than and leading to the feed concentrating channel, projections on said drum, and means on the inner wall of the casing for co-acting with said projections on the drum to move the concentrates 80 and tailings in opposite directions.

7. In a concentrator, a revoluble casing, a revoluble drum within the casing, means for introducing feed into the space between the drum and casing at a point intermediate the 85 ends thereof, projections on the drum and means on the inner wall of the casing for co-acting with said projections to move the concentrates and tailings in opposite directions.

8. In a concentrator, an outer revoluble 90 casing, a revoluble drum within the casing, said drum being hollow and having orifices through its side walls, projections on the outer face of the drum, said projections having perforations and recesses on the edge 95 thereof, means on the inner wall of the casing for co-acting with said projections, and means for introducing feed into the interior of said drum.

9. In a concentrator, a revoluble casing, a 100 revoluble drum within the casing, means for introducing feed into the space between the drum and casing at a point intermediate the ends thereof, projections on the drum and means on the inner wall of the 105 casing for co-acting with said projections to move the concentrates and tailings in opposite directions, and means for introducing wash water into the space between the drum and casing, below the said intermediate 110 point.

10. In a concentrator, an outer revoluble casing, a revoluble drum within said casing having different diameters, and projections on said drum and casing for causing a separation of the concentrates and tailings, and movement of the concentrates in a direction opposite to that of the tailings. 115

11. In a concentrator, an outer revoluble casing, a revoluble drum within said casing 120 forming a feed channel and a wash water channel of different widths communicating with each other, means for introducing feed into the feed channel and means for passing wash water through the wash water channel 125 and delivering it to the feed channel, the feed channel having a discharge opening at one end of the concentrator, and the washing

channel having a discharge opening at the other end of the concentrator.

12. In a concentrator, a revoluble casing, a revoluble drum within the casing, spiral 5 ribs on said drum, said spiral ribs having perforations and recesses on the edges thereof, and means for introducing feed into the space between the drum and casing.

In testimony whereof I have hereunto set my hand at Los Angeles, California, this 10 8th day of September, 1911.

PAUL OSCAR WELS.
